Primary Examiner — Ian Simmons*Assistant Examiner* — Charles Hanson(74) *Attorney, Agent, or Firm* — Calfee, Halter & Griswold LLP**CLAIM**

The ornamental design for an outer hub for a wheel, as shown and described.

DESCRIPTION

FIG. 1 is a perspective view of an outer hub for a wheel, showing our new design;

FIG. 2 is an outer side view thereof;

FIG. 3 is an inner side view thereof;

FIG. 4 is a top view thereof;

FIG. 5 is a bottom view thereof; and,

FIG. 6 is a side view thereof.

The broken lines shown in the drawings are for illustrative purposes only and form no part of the claimed design. The surface shading illustrated in the drawings is provided merely to highlight contour of the design and is not intended to be illustrative texture or gloss.
